LAWRENCE E. LAWSON, OF CHICAGO, ILLINOIS, ASSIGNOR TO SAFETY MINING COMPANY, OF CHICAGO, ILLINOIS, A CORPORATION

HEATER CONSTRUCTION

Application filed June 22, 1929. Serial No. 373,016.

The present invention relates to heat producing devices and is concerned especially with such a device constructed and designed for use in connection with blasting cartridges which employ a liquefied gas or its equivalent as the blasting medium. In cartridges of this type it is essential that the gas be vaporized in a substantially instantaneous manner and for this purpose various chemical 10 heat producing compounds have been developed. In order to properly handle these heat producing compounds it is essential that they be embodied in some form of casing and that provision be made for conveniently igniting 15 the same. Blasting cartridges of the type under consideration usually embody an electrode which is insulated from the body of the cartridge and between which and the cartridge body the heater unit is disposed. 20 Thus, it is necessary to provide the heater unit with a convenient form of contact at each end for engagement with the electrode and the cartridge body respectively. The present invention is principally concerned 25 with the structural characteristics of a heating unit for this purpose. The general construction of the type of cartridge involved is illustrated in the patent to Ferrell, Helmholtz and Crawford No. 1,610,274.

30 It is an object of the present invention to provide a heater unit of the character indicated which will be efficient and reliable and reasonably economical in the cost of manufacture.

35 Another object of the invention is to provide a heater structure of such design as to facilitate the filling or charging thereof with the heat producing compound and to effectively seal the same against leakage of the 40 compounds.

A further object is to provide a heater construction of such design as to substantially eliminate, or, at least, minimize the possibility of short circuiting the heater.

45 One of the more specific objects of the invention is to provide a heating unit which is adapted to be electrically energized and wherein the end closures of the unit form contacts for the electrical energizing means.

In the drawings,

Figure 1 is a view in side elevation of a complete heater unit.

Figure 2 is a view in longitudinal section showing the heater in assembled condition. 55

Figure 3 is a view similar to Figure 2 with the end closures displaced outwardly to illustrate the method of assembly, and

Figure 4 is a transverse section taken on line 4—4 of Figure 2. 60

Referring to the drawings and particularly to Figures 2 and 3 it will be observed that the improved heater unit comprises a substantially cylindrical casing 1 which is formed of a non-metallic and preferably a readily combustible material, a pair of end closures 2 and 3 and an electric squib or matchhead 5. The closures 2 and 3 are formed of metal and are preferably identical in shape although slightly different in size, and the difference in size 65 being such as to accommodate the closure element 3 within the end of tube 1, while the closure element 2 extends over the opposite end of the tube. A suitable conductor 4 having the squib or matchhead arranged intermediate its ends has its opposite end soldered or otherwise electrically connected to the closures 2 and 3 respectively. 70

The conductor 4 is so proportioned with 75 reference to the length of the casing as to permit one or both of the end closures to be removed from the casing. In ordinary practice, the closure 3 is inserted within the end of the tube and glued in place and then the closure 2 is removed and turned laterally in order to leave the corresponding end of the 80 casing unobstructed so that the casing may be conveniently filled with the heat producing compound. After filling the casing, the closure cap 2 is placed over the end of the 85 casing and is glued or otherwise permanently secured in place, thus effectively sealing the casing.

The heat producing compound per se forms no part of the present invention and is therefore not disclosed although a number of suitable mixtures have been developed for this purpose. It is noted, however, that a heater unit of given dimensions is adaptable to a 90 variety of working conditions in view of the 95 100

fact that any desired quantity of the heat producing mixtures within the limits of the capacity of the casing may be used, such portion of the casing as may be left unfilled by the mixture being filled with a suitable inert material such as fuller's earth. The reference character 6 of Figure 2 indicates such an inert filling material.

It will be noted that one of the metallic closure elements is concealed whereas the other is exposed, the purpose of this arrangement being to prevent possible short circuits by the contact of a metal object with the terminals or closures at the opposite ends of the heater casing. This is of particular importance in the use of these heaters in metallic blasting cartridges inasmuch as it often happens that these heaters are so displaced from their normal position as to come into contact with the body of the cartridge, thus giving rise to the possibility of a short circuit and hence failure of the cartridge to do its work. The arrangement shown is quite effective in preventing accidental short circuiting of the heater in this or any similar manner.

In practice the present heater construction is used by placing the internal closure 3 over the end of an electrode provided within the blasting cartridge and insulated from the cartridge body and arranging the opposite closure 2 in contact with a portion of the cartridge body or element in electrical contact therewith. In this way a circuit is completed from the electrode through the heater unit and back to the cartridge casing and in order to energize the heater unit it is only necessary to connect the electrode and cartridge casing with a suitable source of electricity.

It will be apparent that some variations may be made in the specific details of the construction and arrangement of parts and for this reason it is not intended that the present invention be limited other than by the state of the prior art and the scope of the appended claims.

We claim:

1. A heating unit comprising a substantially tubular casing adapted to receive a heat producing mixture, a metallic cup shaped closure member for each end of said casing, one of said members fitting over an end of the casing and the other disposed entirely within the other end of the casing and an electrical igniting device within the casing and having electrical connections with said closure members.

2. A heating unit comprising a non-metallic casing adapted to receive a heat producing compound, a concealed metallic closure for one end of said casing, an exposed metallic closure for the other end of said casing and an electrical igniting device disposed within the casing and having electrical connection with said closures.

3. A heater unit for blasting cartridges comprising a tubular casing adapted to be filled with a heat producing compound, metallic closures for the ends of said casing adapted to serve as electrical contacts, an igniting device within said casing having leads extending toward opposite ends of the casing and connected to the respective closures, said leads being of such length as to permit movement of one of said closures from the end of said casing to enable the latter to be filled.

Signed at Chicago, Illinois, this 19th day of June, 1929.
